DESIGN FOR A COMBINED IRONING MACHINE, LAP BOARD, AND STAND

Andrew H. Gerhardt, Skokie, and Arthur P. Schulz, Hinsdale, Ill., assignors to Electric Household Utilities Corporation, Chicago, Ill., a corporation of Illinois

Application March 19, 1945, Serial No. 118,567

Term of patent 14 years

(Cl. D49—6)

To all whom it may concern:

Be it known that we, Andrew H. Gerhardt and Arthur P. Schulz, citizens of the United States, residing respectively at Skokie and Hinsdale, in the counties of Cook and Du Page and State of Illinois, have invented a new, original, and ornamental Design for a Combined Ironing Machine, Lap Board, and Stand, of which the following is a specification, reference being had to the accompanying drawing, forming a part thereof.

In the drawing:

Fig. 1 is a perspective view showing the front and one end of a combined ironing machine, lap board and stand embodying our new design.

Fig. 2 is a top plan view thereof.

Fig. 3 is an end elevational view thereof.

The characteristic features of our design reside in the combined article disclosed, having a lap board of the configuration shown.

We claim:

The ornamental design for a combined ironing machine, lap board, and stand, substantially as shown and described.

ANDREW H. GERHARDT.
ARTHUR P. SCHULZ.
